UNITED STATES PATENT OFFICE.

FREDERIC WILLIAM RUSSELL, OF REDDITCH, ENGLAND.

SCREWDRIVER.

1,383,429.

Specification of Letters Patent.

Patented July 5, 1921.

Application filed August 29, 1919. Serial No. 320,703.

To all whom it may concern:

Be it known that I, FREDERIC WILLIAM RUSSELL, of 135 Hewell road, Redditch, in the county of Worcester, England, have invented new and useful Improvements in Screwdrivers; and I do hereby declare the following to be a full, clear, and exact description of the same.

My invention relates to screw drivers and 10 more particularly to mechanism for supporting the screw while it is being driven, the apparatus being applicable either to manually operated screw drivers such as the brace type or to power driven devices.

15 The apparatus according to the present invention comprises a sleeve or tube member associated with the blade of the screw driver in such manner that the blade is able to slide therein, said sleeve or tube forming a support for the screw head and a pair of jaws, the extremities of which are arranged to give lateral support to the shank of the screw, the said jaws being locked against being opened by radially applied pressure, but 25 which jaws are automatically unlocked when the screw has nearly reached the full limit of its insertion.

30 My invention also may be applied to screw drivers of the "brace" type, *i. e.*, provided with a cranked portion adapted to be rotated by hand.

According to this application of the invention the driver comprises a crank spindle having a blade at one end and a thrust 35 plate at the other, a screw supporting device including a movable sleeve adapted to support the head of the screw mounted on the spindle adjacent the blade, a pair of radially displaceable shank supporting jaws associated with said sleeve, and a handle rotatably and slidably mounted upon the crank portion of the spindle and a link connecting said handle with the movable sleeve, whereby the amount of screw projecting from the 45 carrier may be adjusted as desired.

In order that my invention may be clearly understood and more readily carried into practice, I have appended hereunto two sheets of drawings, wherein:—

50 Figure 1 is a view in side elevation partly in section.

Fig. 2 is a plan.

Fig. 3 is a view in side elevation, partly in section, showing another form of the invention.

55 Fig. 4 is a plan of the tool shown in Fig. 3.

Fig. 5 is a section on line 5—5 of Fig. 3, and includes a side view of the ratchet mechanism.

Fig. 6 is a view in sectional side elevation 60 showing another form of the device.

Fig. 7 is a view in sectional side elevation showing another form of the device.

Fig. 8 is a view in sectional side elevation showing another form of the device. 65

Fig. 9 is a view in sectional side elevation showing another form of the device.

In the form of the invention illustrated in Figs. 1 and 2 the one main part is produced from a single rod 1 bent substantially 70 to the form of an ordinary carpenter's brace, and having a breast plate 2 at the one end and a screw driver blade 3 at the other end. Conveniently this blade 3 may be made separately and pivoted in a slot 5 on the end of 75 the spindle portion 1, the pivot 4 being substantially at right angles to the driving edge of the blade 3, so as to enable it to compensate for irregularities in the position of the screw when starting. The breast plate 2 80 may be connected to the metal member 1 by means of an anti-friction bearing.

The screw carrier comprises a sleeve 6 adapted to slide along the spindle portion 1, and it carries a pair of jaws 7 the extremities 85 of which project inwardly and which are so arranged that they are locked against being opened by radially applied pressure, such as tilting of the screw, but are automatically unlocked by the screw when it has 90 nearly reached the full limit of its insertion.

The jaws 7 are pivotally mounted at 10, the pivots being carried by slides 11 which are slidably mounted in recesses in the sleeve 6, the slides 11 being movable in a direction corresponding with the length of the spindle. The extremities 8 of the jaws have recesses 9 which engage with the end of a sleeve 62 secured to the lower end of the sleeve 6 and lock the jaws against a radially 100 applied pressure such as would arise from tilting of the screw. The slides 11 are attached to the sleeve 6 by tension springs 12 which act so as to hold the slides normally in their fully receded position. The pivoted 105 jaws 7 are provided with recesses in which are located compression springs 13 which act between the lower ends of slides 11 and the ends of the recesses in the jaws 7 tending to rotate the jaws on the pivots 10 so that the 110 lower ends of the jaws are forced toward each other. The inwardly projecting por-

tions 8 of the jaws 7 are inclined upon the inside at 14 to correspond more or less with the form of conical screw heads, the portions 8 being so shaped that when the screw head is brought against these inclines 14 the jaws 7 are first bodily displaced downwardly in a direction parallel with the length of the spindle until the recesses 9 have moved clear of the end of sleeve 62 so that the jaws 10 are unlocked, after which they are free to turn about their pivots 10, to enable the screw head to pass their extremities 8 and also to allow the screw driver blade 3 to pass through and follow the screw so as to 15 fully insert it. The sleeve 62 is provided with longitudinal slots 63 through which the position of the head of the screw can be seen if desired.

The sleeve 6 together with sleeve 62 is 20 movable axially in relation to the spindle 1 and is provided with one or more (preferably two) inclined openings 15 to enable the screw to be inserted into the sleeve when the screw driver blade 3 is withdrawn beyond these inclined holes.

A tubular handle 16 is rotatably mounted around the aforementioned cranked portion of the tool and is connected to the sleeve 6 by a link 17 in such manner that the handle 30 16 may be moved axially in relation to the cranked portion, taking with it the sleeve 6 which thus moves correspondingly in relation to the spindle 1. In use the handle 16 is gripped by the operating hand and the 35 crank thereby rotated. By this means the operating hand is enabled to control the position of the screw carrying sleeve 6 in relation to the spindle 1, and thereby regulate the extent to which the screw point projects 40 from the tool. In starting a screw it is of great importance that only a minimum amount should project, the screw being firmly supported adjacent its point by the jaws 8 against tilting, and the screw head 45 being supported by the interior surface of the sleeve 6. As the screw enters the material the sleeve 6 and jaws 7 are held stationary or practically so, while the spindle 1 and blade 3 are gradually advanced by 50 pressure on the plate 2. Alternatively when the screw has been driven in sufficiently far for it to become firmly embedded the sleeve 6 and the jaws 7 may be retracted by hand by sliding the handle 16 along the part 1, the jaws 8 remaining in contact with the 55 screw shank but sliding along same.

The movement of the handle along the part 1 is restricted in either direction by a spring buffer or stop.

60 This stop consists of a sleeve 18 slidably mounted on the spindle 1 and having a flange at its end 19. The sleeve 18 is slotted at 20 and a pin 21 passes transversely through the spindle 1. This pin 21 serves to support a washer 22 which is placed around the sleeve 65

18 as shown and a spring 23 is disposed between the washer 22 and the flange 19. In operation the handle can be moved in one direction by compressing the spring; the movement being limited by the length of the 70 slot in the sleeve 18. The motion in the other direction is also limited by the said slot.

The sleeve 6 is provided with a pair of inclined openings 15 for the insertion of 75 screws, this arrangement insuring that one of the openings 15 will always be in a convenient position for receiving the screw. In the construction shown in Figs. 3, 4 and 5 the crank member is made of a spindle 25 carrying a blade 26 pivoted to one end on a pivot 27 disposed substantially at right angles to the driving edge of the blade 26, a 80 crank 28 and a bent spindle 29 carrying the usual breast plate 2 at its end. 85

In this construction I have shown another form of screw supporting mechanism comprising an inner sleeve 31 fixed to a sleeve 30, and upon which slides an outer sleeve 32 including lugs 33 to which are pivoted at 90 34 radially displaceable jaws 35. These jaws are provided with inturned ends 36 having inclined faces 37. Springs 38 are provided acting between the members 32 and the jaws 35, so as to keep the ends 36 pressed toward 95 each other. This inward tendency of the jaws 35 is limited by parts 39 of the jaws contacting the ends of the sleeve 30.

The plain end 40 of each jaw 35 is normally in contact with the sleeve 31, which 100 forms an abutment, locking the jaws 35 against radial displacement. The member 31 is fixed to the sleeve 30 by a grub screw 41, whereas the members 32 carrying the pivots 34 can slide upon the sleeve 30 against 105 the action of a spring 42. If therefore, the member 31 and the sleeve 30 are retracted along the spindle 25, the members 32 carrying the jaws 35 will at first move with the member 31. When however, the screw head 110 forced by the blade 26 comes into contact with the inclined surfaces 37 of the jaws 35 the jaws 35 and members 32 will be held stationary, while the sleeve 30 and member 31 will continue to be retracted. At this point 115 the member 31 will move clear of the ends 40 of the jaws 35 thus setting them free for radial displacement. This displacement actually occurs when the screw head driven by blade 26 forces the ends 36 of the jaws 35 120 apart.

The member 31 can be retracted by the rod 43 pivoted at 44 in a collar 45 rotatably mounted on the part 31. The rod 43 is provided with a pin 46 and washer 47, and a 125 spring 48 is disposed between the washer 47 and the blade 49 fixed to the collar 45. This arrangement forms a spring buffer between the part 31 and the crank 28 and coming into operation at the end of the sliding movement 130

of the handle 54. When the part 31 is fully retracted the washer 47 comes into contact with the surface 50 of the crank 28.

A slot or passage 51 is provided through 5 the crank 28 for the passage of the rod 43. The rod 43 is connected by a pivot 52 to a collar 53 associated with a handle 54.

This form of the apparatus is used in precisely the same manner as that described 10 with reference to Figs. 1 and 2, the screws being inserted in the opening 55 provided in the member 32.

If desired, a toothed wheel 56 may be fixed 15 on the spindle 25 by a pin 57. Coöperating with this wheel 56 are a pair of driving pawls 58 pivotally mounted at 59 to each part of the crank 28. The two pawls 58 are pulled toward each other by a spring 60, thus tending to keep their operative ends in 20 driving contact with the wheel 56. A cam 61 (see Fig. 5) is provided whereby either 25 of the pawls 58 may be thrust out of gear, so that the tool may be used as a ratchet brace in either direction. The cam 61 may be placed in a central position, in which both 30 pawls 58 are in engagement with the wheel 56 when the ratchet mechanism will be inoperative.

In the construction shown in Fig. 6, the 35 spindle 1 is slidably mounted in a sleeve 301, with which is associated a sleeve 311 adapted to support the head of the screw. The jaws 321 which are formed at their lower ends similarly to the jaws shown in Fig. 1, are 40 pivoted at 331 to the sleeve 301. Each jaw 321 is provided with a slot 341 in which is located a spring 351.

In operation as the screw is driven in the 45 screw head engages with the lower ends of the jaws 321 and moves the jaws 321 downwardly against the action of the springs 351. When this action has taken place, the ends 361 of the jaws 321 become free from the shoulders 371 formed on the sleeve 301 thus 50 freeing the jaws 321 and allowing them to be forced apart by the screw or the blade of the screw driver.

In the construction shown at Fig. 7 the 55 blade 1 is slidably mounted in a sleeve 381 and the jaws 391 are pivoted at 401 to a cup shaped sleeve 411. The spring 421 operates between the sleeve 381 and the sleeve 411. The lower ends of the jaws 391 are shaped similarly to the jaws shown in Fig. 1. The 60 jaws 391 are normally locked against outward movement by members 431 which are carried by the sleeve 381. Each jaw 391 is provided with a shoulder 441.

In operation when a screw is being driven, 65 its shank is supported by the lower ends of the jaws 391. As the screw head comes into contact with the ends of the jaws 391 the said jaws together with the sleeve 411 are moved bodily downward until the shoulders 441 pass below the members 431. When

this position is reached the jaws 441 are free to open and release themselves from the screw.

In the construction shown in Fig. 8 the 70 spindle 1 has fixed to it a member 451 provided with cone surfaces at 461 and 471. The jaws 481 are pivoted at 491 to a sleeve 551 slidably mounted upon the spindle 1. The lower ends of the jaws 481 are shaped as described with reference to Fig. 1. 75

Normally the jaws 481 are locked against outward movement by their upper ends 501 being in contact with the member 451. As the spindle 1 moves downwardly, the member 451 travels with it until the ends 501 are 80 reached by the end 461 of the member 451. This position is reached just before the screw 85 is driven home, and in this position the jaws 481 automatically become released from the screw.

The construction shown in Fig. 9 is somewhat similar to that shown in Fig. 8. In this construction however the member 451 is replaced by a sleeve 50^a slidably mounted upon the spindle 1. The sleeve 50^a is supported by a spring 511 acting between a sleeve 521 to which the jaws 481 are pivoted, and a recess in the sleeve 50^a. The spindle 1 is provided with a fixed collar 531 adapted, when the screw is almost driven home, to 90 come into contact with the sleeve 50^a and to move same downwardly until the shoulder 541 is clear of the ends 501 of the jaws 481. In this position the jaws are unlocked and 95 automatically free themselves from the shank or head of the screw. 100

In each of the constructions shown in Figs. 6, 7, 8 and 9, there is a sleeve slidably mounted on the blade 1. These sleeves are numbered respectively 30, 38, 551 and 521. 105 In the operation of each device these sleeves must be held stationary while the blade 1 moves downwardly or the said sleeves must be moved upwardly while the blade 1 is rotated. For this purpose, in each case it is 110 to be understood that the movement of such sleeve is controlled by a handle member, such as shown, for instance, at 16 or 54 in Figs. 1 and 3, which is connected to such sleeve.

What I claim is:— 115

1. A screw driver comprising a spindle having a driving blade at one end, a sleeve slidably mounted upon the said spindle adapted to support the screw head, a handle loosely and slidably mounted upon said spindle and connected to said sleeve to control the relation between the sleeve and the spindle, a fixed abutment upon said sleeve, a pair of radially displaceable jaws pivotally mounted and having a limited sliding movement upon said sleeve, projections upon said jaws adapted to normally engage with the said abutment to lock the jaws against radial displacement, and inwardly directed ends upon said jaws projecting within said 120 125 130

sleeve to support the shank of the screw and adapted to be engaged by the screw head first to move said jaw free of the said abutment and subsequently to radially displace 5 said jaws to allow the screw head and driving blade to pass beyond the jaws when required.

2. A screw driver comprising a spindle having a driving blade at one end, an inner 10 sleeve slidably mounted upon said spindle adapted to support the screw head, an outer sleeve having a limited sliding movement upon said sleeve, a handle loosely and slidably mounted upon said spindle and connected to said inner sleeve to control the relation between the sleeve and the spindle, a fixed abutment upon said sleeve, a pair of radially displaceable jaws pivotally mounted upon said outer sleeve, projections upon 15 said jaws adapted to normally engage with the said abutment to lock the jaws against radial displacement, and inwardly directed ends upon said jaws projecting within said sleeve to support the shank of the screw and 20 adapted to be engaged by the screw head first to move said jaw free of the said abutment and subsequently to radially displace said jaws to allow the screw head and driving blades to pass beyond the jaws when required. 25

3. A screw driver comprising a spindle having a driving blade at one end, an inner sleeve slidably mounted upon said spindle adapted to support the screw head, an outer 30 sleeve having a limited sliding movement upon said sleeve, a flange upon said inner sleeve spaced apart from said outer sleeve, a spring operating between said flange and said outer sleeve, a handle loosely and slidably mounted 35 upon the said spindle and connected to said inner sleeve to control the relation between the sleeve and the spindle, a fixed abutment upon said sleeve, a pair of radially displaceable jaws pivotally mounted upon said outer 40 sleeve, projections upon said jaws adapted to normally engage with the said abutment to lock the jaws against radial displacement, and inwardly directed ends upon said jaws projecting within said sleeve to support the 45 shank of the screw and adapted to be engaged by the screw head first to move said jaws free of the said abutment and subsequently to radially displace said jaws to allow the screw head and driving blade to 50 pass beyond the jaws when required. 55

4. A screw driver comprising a crank spindle having a screw driving blade at one end and a thrust plate at the other end, a screw supporting device including a sleeve 60 for supporting the screw head, and a pair

of radially displaceable members for supporting the shank of the screw, which members are normally locked against displacement, and means for unlocking them when required, and a handle rotatably and slidably mounted on the crank portion of said spindle and a link connecting said handle with said sleeve whereby the amount of screw projecting from sleeve may be adjusted. 65

5. A screw driver comprising a crank spindle having a screw driving blade at one end and a thrust plate at the other end, a screw supporting device including a sleeve for supporting the screw head, and a pair of radially displaceable members for supporting the shank of the screw, which members are normally locked against displacement, and means for unlocking them when required, and a handle rotatably and slidably mounted on the crank portion of said spindle and a link connecting said handle with said sleeve whereby the amount of screw projecting from sleeve may be adjusted, 70 and a spring buffer operating between said handle and said sleeve at one end of the sliding movement of said handle. 75

6. A screw driver comprising a crank spindle having a screw driving blade at one end and a thrust plate at the other end, a screw supporting device including an inner sleeve for supporting the screw head, a pair of radially displaceable jaws for supporting the shank of the screw, an outer sleeve slidably mounted upon said inner sleeve, lugs on 90 said outer sleeve to which said jaws are pivoted, an abutment on said inner sleeve which normally locks said jaws against displacement, means for automatically unlocking them when the screw has nearly reached the 95 full limit of its insertion, including a handle rotatably and slidably mounted on the crank portion of said spindle, and a link connecting said handle with the said abutment. 100

7. A screw driver comprising a crank spindle having a screw driving blade at one end and a thrust plate at the other end, a screw supporting device including a sleeve for supporting the screw head, said sleeve being disposed around said screw driving blade and able to move longitudinally with respect to said spindle, and a handle rotatably and slidably mounted on the crank portion of said spindle, and a link connecting said handle with said sleeve whereby the amount of screw projecting from the sleeve may be 110 adjusted. 115

In testimony whereof I affix my signature.

FREDERIC WILLIAM RUSSELL.
